UNITED STATES PATENT OFFICE.

CASPER BLOOMBERG, OF NEW YORK, N. Y., ASSIGNOR TO CROWN SUSPENDER COMPANY,
OF NEW YORK, N. Y., A CORPORATION OF NEW YORK.

CIGARETTE-CASE.

1,285,602.

Specification of Letters Patent. Patented Nov. 26, 1918.

Application filed March 28, 1918. Serial No. 225,205.

To all whom it may concern:

Be it known that I, CASPER BLOOMBERG, a citizen of the United States, residing at New York city, in the county of New York and State of New York, have invented certain new and useful Improvements in Cigarette-Cases, of which the following is a specification.

My invention relates to improvements in cigarette cases and my object is the production of a moisture proof case which will keep the cigarettes in proper condition, hold a large number in small bulk, protect them against breakage and provide a pocket for matches.

In the drawing Figure 1 is a perspective view of my improved case, partly broken away; and Fig. 2 a sectional view of the structure of Fig. 1.

In making my case I employ a rubberized or water-proofed fabric, the use of which keeps the cigarettes and matches in proper condition.

One piece of the rubberized material is cut and folded to form a pocket having the front 1, back 2 and flap 3 with the edges 5, 6 and 7 sewed together and preferably bound as is also the top edge 4 and the flap edge 8.

Another piece of rubberized material is folded to form a second pocket having the front 9 and back 10 with the edges 11, 12

and 13 sewed together and preferably bound as are the top edges 14 and 15.

The two pockets are made the same size 35 and the front 1 of the first pocket and the back 10 of the second pocket are sewed together at 15', at a distance from the edges, but are left unsewed at the top to form a match pocket.

The case therefore has a front and rear cigarette holding pocket with a smaller match pocket between them and, by reason of the smaller match holding pocket, a bellows like case is produced as shown.

To stiffen the case and protect the cigarettes against breakage U-shaped metal frames 16 and 17 are placed one in each cigarette pocket.

A fastener 18, 18' on the flap 3 and front 50 9 serves to hold the flap in closed position.

I claim:—

A cigarette case comprising a pocket with an open top, a flap extending from the top, a second pocket with an open top, the two 55 being secured together at a distance from the sides and bottom whereby a third and smaller pocket is formed between the two, U-shaped metal frames in each of the two larger pockets and means for holding the 60 flap in closed position.

In testimony whereof I have affixed my signature.

CASPER BLOOMBERG.
